CLAIM

The ornamental design for a flatware handle or similar article, as shown and described.

DESCRIPTION

FIG. 1 is a front elevational view of a flatware handle showing my new design;

FIG. 2 is a right side elevational view thereof, the side opposite being a mirror image thereof;

FIG. 3 is a rear elevational view thereof;

FIG. 4 is a front elevational view thereof on a reduced scale. The broken line showing of the spoon bowl and shank of the handle is for illustrative purposes only and forms no part of the claimed design; and

FIG. 5 is a cross-sectional view thereof taken on line 5—5 of FIG. 1.
